COUNTER DRIVE MECHANISM

Mark M. Hennessy, Milwaukee, Wis., assignor to
 Durant Manufacturing Company, Milwaukee,
 Wis., a corporation of Wisconsin

Application June 29, 1934, Serial No. 732,988

7 Claims. (Cl. 74—389)

The invention relates to counters and more particularly to those recording devices in which one of a plurality of counters is adapted to be selectively driven from a common drive shaft. 5 The object of the invention is to provide a simple and efficient mechanism for shifting the drive from one counter to another through the simple shifting action of a lever, the inoperative counter being locked or restrained from actuation. 10 More particularly the present invention embodies a toggle shift arrangement for selectively bringing one of the gears of the drive mechanism into operative position.

The invention further consists in the several 15 features hereinafter set forth and more particularly defined by claims at the conclusion hereof.

In the drawing:

Fig. 1 is a plan view of a recording device embodying the invention;

Fig. 2 is a detail sectional view taken on the 20 line 2—2 of Fig. 1;

Fig. 3 is a detail plan view of the mechanism embodying the invention.

Referring to the drawing, the numeral 4 designates the drive shaft which may be driven in any 25 suitable manner from any suitable source of power and is here shown as driven from a centrally disposed shaft 5 through suitable gearing (not shown) and is connected through gearing hereinafter described to either one of the counter 30 shafts 6 which have the usual counter wheels 7 thereon indicated in Fig. 1 but not shown in detail herein.

A shiftable frame 8 is mounted to swing about 35 the shaft 4 as a center and has the gears 9 journaled thereon in constant mesh with a gear 10 on the drive shaft 4 and adapted to be alternately moved into mesh with a gear 11 on either 40 of the shafts 6. The frame 8 is maintained in a central inoperative position by a detent 12 urged by a spring 13 to engage a recess 14 in said frame. The frame is held in either of its gear driving positions by toggle mechanism connected with the ends of said frame and comprising in each instance a toggle link member 16 45 pivotally connected at one end by a pin 17 to said frame and at its other end formed into a shoulered pin 18 to receive one end of a spring 19 whose other end seats on the spring seat plug 20 in threaded engagement with the casing 21. The 50 swinging movement of the frame 8 is limited by a pin 22 fixed to the casing and working in an arcuate slot 23 in said frame.

The frame 8 is shifted by means of a lever 24 55 pivoted intermediate its ends on the shaft 25

and having one arm formed to engage in a slot 26 in said frame while the other arm projects through a slot 27 in the cover 28 and forms a handle 29.

With the above described arrangement when 5 the handle 29 is shifted toward the right, the frame 8 is shifted or swung to bring the right hand gear 9 into mesh with the gear 11 on the right hand counter shaft 6 and is held in this biased position by the action of the springs 10 19 thereon through the members 16 and when said handle is shifted toward the left the left hand gear 9 meshes with the left hand counter gear 11 and the frame is held in this position 15 as before by the springs 19 and members 16. Thus either counter may be selectively driven from the drive shaft 4 to take care for example of day and night production.

To prevent slippage of the undriven counter each counter has a locking detent 30 associated 20 with it in the form of a bell crank lever pivoted at 31 to the casing and provided with a tooth 32 normally urged by a spring 33 into engagement with one of the teeth of the gear 11, the other arm 34 of said lever adapted to engage a cam 25 surface 35 of the frame 8 so that when said frame is shifted, one of these cam surfaces 35 will act on the lever associated therewith to swing said lever to release its tooth 32 from engagement with the adjacent gear 11. Thus when the 30 handle 29 is shifted to the right to establish the drive to the right hand counter shaft 6, the detent 30 for the gear 11 of this shaft is shifted to release position and similarly when the left hand drive is established, the detent 30 for the 35 left hand counter shaft 6 is released.

I desire it to be understood that this invention is not to be limited to any particular form or arrangement of parts except in so far as such limitations are included in the claims.

What I claim as my invention is:

1. In a device of the character described, the combination of a drive shaft and a pair of counter shafts, a separate gearing connection between said drive shaft and each of said counter shafts 45 including a shiftable idler gear to connect said drive shaft with one of said counter shafts, a shiftable frame on which said shiftable idler gears are mounted, means for holding said frame in either of its driving positions, means for restraining the movement of the undriven counter shaft, and means operatively connected to said frame for shifting the same.

2. In a device of the character described, the combination of a drive shaft and a pair of coun- 55

- ter shafts, a separate gearing connection between said drive shaft and each of said counter shafts including a shiftable idler gear to connect said drive shaft with one of said counter shafts, a shiftable frame on which said shiftable idler gears are mounted, means for holding said frame in either of its driving positions, means for normally restraining the movement of each counter shaft, said last named means for one of said counter shafts being releasable by said frame on its movement to a driving position, and means operatively connected to said frame for shifting the same.
3. In a device of the character described, the combination of a drive shaft and a pair of counter shafts, a gear on said drive shaft, a gear on each of said counter shafts, a swinging frame, idler gears on said frame constantly meshing with the gear on said drive shaft and alternately respectively meshing with the gears on said counter shafts to establish alternate driving connections from said drive shaft to said counter shafts on the movement of said frame to its driving positions, means yieldingly engaging opposite sides of said frame for holding said frame in either of its driving positions, means for restraining the movement of the undriven counter shaft, and means operatively connected to said frame for shifting the same.
4. In a device of the character described, the combination of a drive shaft, and a pair of counter shafts, a separate gearing connection between said drive shaft and each of said counter shafts including a shiftable idler gear to connect said drive shaft with one of said counter shafts, a swinging frame on which said shiftable idler gears are mounted, a spring and a link member associated with each side of said frame to hold the frame in either of its positions in which one of the shiftable idler gears is in a driving position, and a lever operatively connected to said frame for shifting the same.
5. In a device of the character described, the combination of a drive shaft having a gear mounted thereon, a pair of counter shafts, a

gear on each of said counter shafts, a swinging frame, a swinging lever connected to swing said frame, a separate releasable gearing connection between the gear on said drive shaft and each of said counter shafts including an idler gear mounted on said frame and movable therewith, into and out of operative relation to the gear on the adjacent counter shaft, and toggle means for holding said frame in the driving position for either of its gears.

6. In a device of the character described, the combination of a drive shaft, a pair of counter shafts, a gear on said drive shaft, a gear on each of said counter shafts, a swinging frame, idler gears on said frame constantly meshing with the gear on said drive shaft and alternately respectively meshing with the gears on said counter shafts to establish alternate driving connections from said drive shaft to said counter shafts on the movement of said frame to its driving position, the center line of each counter shaft and the gear on said frame when meshing therewith being at substantially right angles to the line of centers between said gear on said frame and the drive shaft, means operatively connected to the frame for moving the same to its driving positions, and means for holding said frame in either of its driving positions.

7. In a device of the character described, the combination of a drive shaft, a pair of counter shafts, a gear on said drive shaft, a gear on each of said counter shafts, a swinging frame, idler gears on said frame constantly meshing with the gear on said drive shaft and alternately respectively meshing with the gears on said counter shafts to establish alternate driving connections from said drive shaft to said counter shafts on the movement of said frame to its driving position, means including a spring at each side of said frame, and guide means for each spring pivoted on said frame to hold the frame in either of the positions in which one of said idler gears is in a driving position, and means operatively connected to said frame for shifting the same.

MARK M. HENNESSY. 45
